UNITED STATES PATENT OFFICE.

DAVID A. MOYER, OF BIRDSBORO, PENNSYLVANIA, ASSIGNOR TO UNITED SHOE MACHINERY CORPORATION, OF PATERSON, NEW JERSEY, A CORPORATION OF NEW JERSEY.

MACHINE FOR SHAPING UPPERS OVER LASTS.

Application filed August 24, 1920. Serial No. 405,632.

To all whom it may concern:

Be it known that I, DAVID A. MOYER, a citizen of the United States, residing in Birdsboro, in the county of Berks and State of Pennsylvania, have invented certain Improvements in Machines for Shaping Uppers over Lasts, of which the following description, in connection with the accompanying drawings, is a specification, like reference characters on the drawings indicating like parts in the several figures.

This invention relates to machines for shaping uppers over lasts, and more particularly to machines having means for laying the margin of the upper inwardly over the bottom of the last. The invention is herein shown in its application to a machine provided with means for pulling the upper over the last and means for lasting the toe of the shoe, but it will be understood that in many of its aspects the invention is not limited to combined pulling-over and lasting machines.

An object of the invention is to improve the operation of overlaying means upon a shoe; and with this and other ends in view, a feature of the invention consists in novel means for controlling the relation between the overlaying means and the shoe in the overlaying operation. The invention has important advantages as applied to an organization wherein the resistance encountered in the overlaying operation may cause a relative pressure relaxing movement of the shoe and the overlaying means in a direction transverse to the plane of the last bottom. Such an organization is shown, for example, in United States Letters Patent No. 1,280,613, granted on October 1, 1918, upon an application of Orrell Ashton, wherein facility in positioning the toe wipers relatively to the shoe is afforded by a yielding support which permits the wipers to be tipped in directions transverse to the plane of the sole as the operator advances and places them in position for their operative movement over the shoe. In order to prevent the wipers in their overwiping operation from tipping unduly in response to resistance of the shoe materials, and to insure effective overwiping pressure, the wiper carrier in the construction herein shown has means for engaging the shoe on the sloping

end or top face of the toe to render the shoe effective with a wedging action serving to prevent the wipers from relaxing their pressure on the upper and it may be also to force the wipers toward the plane of the sole and thus to increase their overwiping pressure as they are advanced over the shoe. Insurance is thus afforded that the wipers in their advancing and closing movement shall wipe the margin of the upper materials firmly over the feather and against the shoulder or rib of the sole and also draw the materials tightly and smoothly over the edge of the sole.

In a further important aspect, as applied to an organization in the use of which the overlaying means is positioned manually in relation to the shoe prior to its operative movement, a feature of the invention consists in novel means to assist in positioning the overlaying means in the proper relation to the shoe. In the construction shown the means provided for engagement with the top of the toe, as above described, is adapted to be manipulated by the operator as he advances the wipers into engagement with the shoe to assist in steadyng the wipers and in bringing them to the proper overwiping plane, and it may be also to press them toward the plane of the last bottom after they have been advanced slightly over the edge of the sole to insure that both the wipers and the margin of the sole shall be positioned in the proper relation to said plane in the overwiping operation.

While the invention is herein illustrated in its application to a machine of the type shown in said prior Ashton patent, it will be understood that no restriction is thereby implied with respect to the field of utility of the invention. It will also be understood that while the invention is illustrated in its application to turn shoe work, it is not thus limited in utility, and the term "sole" is accordingly used herein in its generic sense as applicable to the insole of a welt or other type of shoe as well as to the sole of a turn shoe.

The above and other features of the invention, including certain details of construction and combinations of parts, will now be described with reference to the accom-

panying drawings and pointed out in the appended claims.

In the drawings:

Fig. 1 is a view in side elevation of the head portion of the illustrative machine,

Fig. 2 is a perspective view of a portion of the toe wiper mechanism, and

Fig. 3 is a view substantially in side elevation, with parts in section, further illustrating the use of the invention.

Since the features common to the construction herein shown and to prior machines of the illustrative type are shown and described in detail in prior patents including the patent above mentioned, said features will be referred to herein only in as far as is necessary for an understanding of the invention.

Machines of this type include in their organization a toe gripper 2 and opposite side grippers 4 connected respectively to updraw levers 6 and 8 which are operated by cams on a cam shaft 10 to seize and pull the upper against the resistance of a sole rest 12, whereupon the machine comes automatically to a stop to permit inspection and any necessary adjustment of the upper. Upon a subsequent starting of the machine, shoe supporting devices mounted on arms 14 are swung inwardly to operative position, and operative movement is then imparted to mechanism mounted on arms 16 and 18 for overlaying and fastening the margin of the upper at the toe and at the opposite sides of the forepart of the shoe. For overlaying the upper at the toe the machine has end embracing wipers which may be of any suitable construction and are herein shown as constructed substantially as shown and described in United States Letters Patent No. 1,406,230, granted on Feb. 14, 1922, upon an application of Bernhardt Jorgensen. These wipers are supported on the front arm 16 and are advanced and closed in a well-known manner by movements of the front and side arms 16 and 18.

In the use of machines of this type the toe gripper is released and the wipers are advanced and tipped manually to position them in engagement with the upper in the proper overwiping plane while the machine is at rest after the upper pulling operation and before it is started to effect the overlaying and fastening operations. In order to permit such manipulation of the wipers, they are mounted, as explained in said prior patents, upon a wiper support or carrier 22 which has a lengthwise slot 24 to receive a pin 26 projecting downwardly from the front arm 16, and a spiral spring 28 bears upwardly against the carrier to hold it in position while permitting it to be tipped and advanced into engagement with the shoe to position the wipers in the proper relation to the plane of the sole. In the subsequent

operation of the arm 16 the pin 26 is advanced along the slot 24 until the tackers 29 arrive in operative relation to the wipers, and the wiper carrier is then advanced to force the wipers rearwardly over the shoe 70 bottom substantially simultaneously with their inward closing movement at the sides through the operation of the arms 18. As shown in the prior patents, the wiper carrier 22 is adapted to support different wipers at 75 its opposite ends, for example, right and left wipers, and to be turned about the pin 26 to position either set of wipers for operation on the work.

For the purposes of this invention there is secured at each end of the wiper carrier 22, under the respective wipers, a bracket 30 having a depending arm which supports a device for engaging the sloping end or top face of the toe of the shoe to assist in positioning the wipers and in maintaining them in their proper wiping plane. This device comprises a slide 32 mounted for upward and downward movement on a plate 33 adjustably secured on the depending arm of the bracket 30, the plate having a pin 34 which extends through a slot 35 in the slide and has a head which overlaps the slide. The slide 32 is provided with outturned ears 36 and 37 to receive and guide a holder 38 on which is mounted a roll 40 for engagement with the sloping top face of the toe of the shoe. The holder 38 comprises a stem projecting downwardly through the lower ear 36 and having an upper end portion 100 shaped to fit in a rectangular recess in the ear 37 to prevent turning movement of the holder. Between a shoulder on the upper end portion of the holder 38 and the lower ear 36 is a spring 42 which tends to force the holder upwardly and maintains it normally at an upper limit of movement determined by engagement of a pin 44 with the ear 36. The slide 32 is provided on its opposite sides with flanges which partially embrace the depending arm of the bracket 30 and are provided with rack teeth in engagement with a series of gear teeth formed on flange extensions 46 of an operating member 48 which is mounted on a pivot 50 supported on flange extensions of the plate 33. The member 48 has a depending flat plate adapted to be engaged by the thumb of the operator to turn the member about its pivot and through the gear and rack teeth to force the slide 32 upwardly and press the roll 40 against the shoe. A clamping bolt 52 extending through a slot in the plate 33 permits this plate and the parts supported upon it to be adjusted upwardly or downwardly and serves to hold the parts in adjusted position.

In the use of the above described construction the operator, after the machine has come to a stop with the upper held under

- tension, releases the toe portion of the upper from the toe gripper, and by grasping the depending arm of the bracket 30 advances the wipers into engagement with the shoe, 5 tipping the wiper carrier 22 as required in order to position the wipers in the proper relation to the plane of the shoe bottom for the overwiping operation. As the operator grasps the bracket 30 and advances the wiper carrier, he presses his thumb on the member 48 and by turning it about its pivot 50 forces the roll 40 upwardly against the sloping end or top face of the toe under the yielding pressure of the spring 42. The roll thus 10 assists in steadyng the wipers as they are manipulated to place them in the proper relation to the shoe, and by the use of the member 48 and the connected roll the operator is also assisted in bringing the wipers 15 down to the proper wiping plane after they have been advanced, for example, slightly over the edge of the sole. By the use of this mechanism the margin of the sole may thus be readily pressed down into the proper 20 relation to the bottom of the last in case it may have been turned up slightly from the last, and both the sole and the wipers may be positioned in proper relation to the last to insure a tight and effective overwiping 25 of the upper in the operative movement of the wipers. Having positioned the wipers in their proper plane with the assistance of the toe engaging means, the operator retains his hold on the bracket 30 and on the member 30 during the second stage of the cycle of the machine in which the overlaying and fastening operations are performed. The roll 40 is thus held yieldingly against the sloping face of the toe as the wiper carrier 40 receives its forward movement to advance the wipers over the shoe and renders the shoe effective with a wedging action tending to force the wipers downwardly toward the plane of the sole as they are advanced over 45 the shoe, insuring that the wipers shall be advanced in such relation to the shoe as to wipe the upper tightly and firmly over the feather and against the shoulder of the sole. As the wipers complete their operative movement 50 the fastening tacks are driven and the parts of the machine are then returned to starting position and the shoe is released.
- Having described the invention, what I claim as new and desire to secure by Letters 55 Patent of the United States is:
1. In a machine of the class described, the combination with shoe positioning means and overlaying means relatively movable in a direction substantially parallel to the plane 60 of the shoe bottom to lay the margin of the upper inwardly over the sole of the shoe, of a device arranged for engagement with the shoe and to be rendered operative by such relative movement of the shoe and the 65 overlaying means to produce compression
- between the shoe and said means in a direction transverse to the plane of the shoe bottom in the overlaying operation.
2. In a machine of the class described, the combination with shoe positioning means 70 and overlaying means relatively movable in a direction substantially parallel to the plane of the shoe bottom to lay the margin of the upper inwardly over the sole of the shoe, of a device operatively connected to said overlaying means and arranged for engagement with the sloping top face of the shoe to be rendered operative by such relative movement of the shoe and the overlaying means to produce compression 75 between the shoe and said means in a direction transverse to the plane of the shoe bottom, and manual means enabling the operator to control said device during the overlaying operation.
3. In a machine of the class described, the combination with shoe positioning means and overlaying means relatively movable in a direction substantially parallel to the plane of the shoe bottom to lay the margin 80 of the upper inwardly over the sole of the shoe and relatively movable also in a direction transverse to said plane, of a device mounted in substantially fixed relation to said overlaying means with respect 85 to bodily movement parallel to the plane of the shoe bottom and arranged for engagement with the top face of the shoe to control the relation between the shoe and said means with respect to movement transverse 90 to the plane of the sole in the overlaying operation.
4. In a machine of the class described, the combination with shoe positioning means and overlaying means relatively movable in 105 a direction substantially parallel to the plane of the shoe bottom to lay the margin of the upper inwardly over the sole of the shoe and relatively movable also in a direction transverse to said plane, of a device mounted in substantially fixed relation to said overlaying means with respect 110 to bodily movement parallel to the plane of the shoe bottom and arranged to be pressed by the operator against the top face of the 115 shoe during the overlaying operation to control the relation between the shoe and said means with respect to movement transverse to the plane of the sole.
5. In a machine of the class described, the 120 combination with means movable to lay the margin of an upper inwardly over the bottom of a last, of a device operatively connected to said overlaying means to move inwardly with it in the overlaying of the 125 upper and arranged to engage the top face of the shoe to control the movement of said means in its operation upon the shoe.
6. In a machine of the class described, the combination with means movable to lay 130

the margin of an upper inwardly over the bottom of a last, of a device connected to said overlaying means to be moved inwardly by said means in the overlaying of the 5 upper and arranged to be pressed by the operator against the top face of the shoe while moving inwardly along said face in the overlaying operation to control said overlaying means in its operation upon the 10 shoe.

7. In a machine of the class described, the combination with means movable to lay the margin of an upper inwardly over the bottom of a last, of a device constrained to 15 move inwardly with said overlaying means and arranged for engagement with the sloping top face of the shoe to render the shoe effective to force said overlaying means toward the plane of the last bottom in the 20 overlaying operation.

8. In a machine of the class described, the combination with end embracing wipers mounted for movement to wipe the margin of an upper inwardly over the bottom of a 25 last and movable also in a direction transverse to the plane of the last bottom, of a device constrained to move inwardly with said wipers and arranged to be pressed by the operator against the top face of the shoe 30 to control the wipers with respect to the plane of their operative movement.

9. In a machine of the class described, the combination with end embracing wipers mounted for movement to wipe the margin 35 of an upper inwardly over the bottom of a last and movable also in a direction transverse to the plane of the last bottom, of a device constrained to move inwardly with said wipers and arranged to engage the sloping top face of the end of the shoe to render the shoe effective to force the wipers toward the plane of the last bottom, and means enabling the operator to press said device against the shoe in a direction transverse to 40 said plane during the operation of the wipers.

10. In a machine of the class described, the combination with toe embracing wipers movable to wipe the margin of an upper inwardly over the bottom of a last, of a device arranged for engagement with the toe 50 of the shoe and for operation in response to the movement of the wipers to produce compression between the shoe and the wipers in 55 a direction transverse to the plane of the last bottom in the overwiping operation.

11. In a machine of the class described, the combination with toe embracing wipers and a wiper support mounted for movement 60 to wipe the margin of an upper inwardly over the bottom of a last and movable also in directions transverse to the plane of the last bottom, of a device on said wiper support constrained to move inwardly with 65 said wipers in engagement with the top face

of the toe of the shoe to control the wipers with respect to the plane of their overwiping movement.

12. In a machine of the class described, the combination with toe embracing wipers 70 mounted for movement to wipe the margin of an upper inwardly over the bottom of a last and movable also in directions transverse to the plane of the last bottom, of a device supported for inward movement 75 with said wipers and operative by such inward movement through engagement with the sloping top face of the toe of the shoe to render the shoe effective to force the wipers toward the plane of the last bottom in their 80 overwiping movement.

13. In a machine of the class described, the combination with end embracing wipers and a wiper carrier, of a wiper controlling member supported by the wiper carrier for 85 engagement with the top face of the shoe, said member being movable relatively to the wiper carrier in directions transverse to the plane of the shoe bottom and fixed relatively to said carrier with respect to 90 movement parallel to said plane, and operating means connected to said wiper controlling member to enable the operator to press said member against the top face of the shoe during the operation of the wipers. 95

14. In a machine of the class described, the combination with end embracing wipers and a wiper carrier, of a wiper controlling member supported by the wiper carrier for engagement with the top face of the shoe, 100 said member being movable relatively to the wiper carrier in directions transverse to the plane of the shoe bottom and fixed relatively to said carrier with respect to movement parallel to said plane, and an operating member also supported by the wiper carrier and arranged to be turned by the pressure of the operator's hand to hold 105 said wiper controlling member against the shoe during the operation of the wipers. 110

15. In a machine of the class described, the combination with end embracing wipers movable to wipe the margin of an upper inwardly over the bottom of a last, of a member mounted for movement with said wipers 115 and arranged to engage the shoe to produce compression between the wipers and the bottom of the last in the overwiping operation, and spring means between said member and the wipers arranged to yield 120 in response to resistance of the shoe.

16. In a machine of the class described, the combination with end embracing wipers and a wiper carrier, of a bracket secured to 125 said wiper carrier, a wiper controlling member supported on said bracket for movement in directions transverse to the plane of the shoe bottom and arranged to engage the top face of the shoe, and manually operative means on said bracket to 130

press said member against the shoe during the operation of the wipers.

17. In a machine of the class described, the combination with end embracing wipers 5 and a wiper carrier, of a bracket mounted on said carrier, a slide movable on said bracket in directions transverse to the plane of the shoe bottom, a roll carried by said slide for engagement with the top face of 10 the shoe, and manually operated means for moving said slide to press the roll against the shoe.

18. In a machine of the class described, the combination with power operated over- 15 laying means arranged to be positioned manually in engagement with a shoe prior to its operative movement over the shoe, of a device operatively connected to said over-laying means for power movement with 20 said means and arranged to engage the top face of the shoe to assist in manually positioning said means relatively to the plane of the shoe bottom.

19. In a machine of the class described, 25 the combination with power operated wipers arranged to be positioned manually in engagement with a shoe prior to their operative movement over the shoe, of a member mounted for power movement length- 30 wise of the shoe with said wipers and movable also in directions transverse to the plane of the wipers, and manual means for pressing said member against the top face of the shoe to assist in positioning the wipers relatively to the plane of the shoe bottom.

20. In a machine of the class described, the combination with power operated wipers arranged to be positioned manually in engagement with a shoe prior to their operative movement over the shoe, of a device 40 mounted for power movement with said wipers and arranged to engage the sloping top face of the shoe to assist in positioning the wipers relatively to the shoe and to 45 render the shoe effective to force the wipers toward the plane of the shoe bottom in the overwiping operation.

21. In a machine of the class described, the combination with power operated wipers 50 arranged to be advanced to engage a shoe and to be positioned manually relatively to the plane of the last bottom prior to their operative movement over the shoe, of a device mounted for power movement with said 55 wipers and arranged to be pressed by the operator against the top face of the shoe to assist in forcing the wipers and the margin of the sole toward the plane of the last bottom prior to the operative movement of the 60 wipers over the shoe.

22. In a machine of the class described, the combination with power operated wipers and a wiper carrier arranged to be advanced and adjusted manually to position the wipers 65 relatively to a shoe prior to their operative

movement over the shoe, of a member on said wiper carrier arranged to be engaged by the hand of the operator for positioning the wipers, and a device movably mounted on said member to be pressed by the operator against the top face of the shoe to assist in positioning the wipers relatively to the shoe.

23. In a machine of the class described, the combination with power operated wipers 70 and a wiper carrier arranged to be advanced and adjusted manually to position the wipers relatively to a shoe prior to their operative movement over the shoe, of a bracket on said wiper carrier arranged to be engaged by the 75 hand of the operator for positioning the wipers, a member movable on said bracket into engagement with the sloping top face of the toe of the shoe, and an operating member on the bracket arranged to be turned 80 by the operator to press said shoe engaging member against the shoe as the wipers are positioned relatively to the shoe.

24. In a pulling-over machine, the combination with means for pulling an upper 90 over a last, of power operated wipers arranged to be positioned manually in engagement with the toe of the shoe after the upper has been pulled, and a device mounted for power movement with said wipers 95 and arranged to engage the sloping end face of the toe of the shoe to render the shoe effective to press the wipers toward the plane of the last bottom during their movement over the shoe.

25. In a pulling-over machine, the combination with means for pulling an upper over a last, of power operated wipers arranged to be positioned manually in engagement with the toe of the shoe after the upper 100 has been pulled, and a device mounted for power movement with said wipers and arranged to be pressed by the operator against the sloping end face of the toe of the shoe to assist in positioning the wipers relatively to the shoe and to be held by the operator against the shoe to render the shoe effective to force the wipers toward the plane of the last bottom during the overwiping operation.

26. In a machine of the class described, the combination with overlaying means mounted for movement to lay the margin of an upper inwardly over the bottom of a last, of a device arranged to engage the sloping top face of the shoe and to be rendered operative through such engagement by the inward movement of said overlaying means to effect relative movement between said means and the shoe in a direction transverse to the plane of the shoe bottom.

27. In a machine of the class described, the combination with wipers mounted for movement lengthwise of a shoe to wipe the margin of the upper inwardly, of a device operatively connected to said wipers to move 120

with them lengthwise of the shoe in engagement with the top face of the toe of the shoe to effect compression between the shoe and the wipers, said device comprising a member 5 slidingly mounted for movement in directions transverse to the plane of the shoe bottom and having rack teeth thereon, and a member having teeth engaging said rack teeth and arranged to be manipulated by the 10 operator to hold the device in engagement with the top of the toe during the over-wiping movement of the wipers.

28. In a machine of the class described, the combination with wipers and a wiper 15 support mounted for movement lengthwise of a shoe, of a device carried by said wiper

support for effecting compression between the wipers and the shoe as the wipers are moved lengthwise of the shoe, said device comprising a rack slide movable in directions transverse to the plane of the shoe bottom, a roll carried by said rack slide for engagement with the top of the toe of the shoe, a spring between said roll and the slide to press the roll yieldingly against the shoe, 20 and a member connected to said rack slide to enable the operator to apply pressure yieldingly to the roll through said spring.

In testimony whereof I have signed my name to this specification.

DAVID A. MOYER.
